UNITED STATES PATENT OFFICE.

MORITZ SCHENKEL, OF CHARLOTTENBURG, GERMANY, ASSIGNOR TO SIEMENS-SCHUCKERTWERKE GESELLSCHAFT MIT BESCHRÄNKTER HAFTUNG, OF SIEMENSSTADT, NEAR BERLIN, GERMANY, A GERMAN CORPORATION.

ELECTRIC VACUUM APPARATUS.

1,410,606.

Specification of Letters Patent. Patented Mar. 28, 1922.

Application filed December 4, 1920. Serial No. 426,423.

To all whom it may concern:

Be it known that I, MORITZ SCHENKEL, a citizen of the German Empire, residing at Charlottenburg, Germany, have invented 5 certain new and useful Improvements in Electric Vacuum Apparatus, (for which I have filed applications in Germany Dec. 7, 1918, and Austria Nov. 19, 1919,) of which the following is a specification.

10 My invention refers to electric vacuum apparatus and more especially to the kind of apparatus described and claimed in Letters Patent of the United States Nos. 1,326, 972 and 1,328,597 granted to me on January 15 6th and January 20th, 1921, respectively, the said apparatus substantially consisting of an evacuated receptacle containing a self-sustaining anode body formed of annular anodes and partitions alternately disposed 20 one above the other, such anode body dividing the receptacle in two parts. The particular object of the present invention is to render the said composite anode body more perfectly air-tight in order to prevent the 25 electric arc formed between one of the annular anodes and the annular mercury cathode from jumping over to the other side of the anode body in case a high vacuum exists on that side. For this reason it has been 30 found preferable to keep the diminution of pressure on this side of the electrodes rather low or even to admit atmospheric pressure. However the greater difference of 35 pressure existing in such a case on the two sides of the electrode body renders it imperative to make this body as perfectly air-tight as possible. This is the more necessary as the arc tends to wander from the front face 40 of the anode to the joint, the seals provided therein thus gradually filling with condensed 45 mercury and in consequence thereof becoming conductive so that the partitions inserted between the annular anodes are ultimately destroyed and a sparking over 50 towards the receptacle wall takes place at the points where the electrodes are passing through.

According to the present invention the 55 joints between the anodes and the partitions are rendered air-tight by covering them on the side averted from the arc with a liquid, preferably with a liquid metal such as mercury.

In the drawings affixed to this specifica-

tion and forming part thereof a number of 55 modifications of a device constructed in accordance with the present invention are illustrated in a diagrammatic manner. In the drawings—

Fig. 1 is a vertical section of one half 60 of a vacuum apparatus with the anode body according to the present invention arranged therein.

Figs. 2 to 5 are similar views of anode bodies differing in the form of the anodes 65 and partitions.

Referring to Fig. 1, 1 is the rectifier vessel, 2 is its cover, 3 is a seal securing an airtight fit between the vessel and cover. 5, 6, 7 are three annular anodes, 8, 8 are hollow 70 conductors adapted to conduct the current to said anodes and to feed a cooling medium such as water into channels provided to this end within said anodes. 9, 9 are seals interposed between the cover openings and the 75 conductors passing through them. 20 is a mercury cathode which may however be replaced by a cathode of any other suitable kind such as for instance a glow cathode of 80 a suitable form.

10, 11, 12, 13 are partitions made of a heat resisting insulating material such as porcelain, the said partitions being interposed between the anodes as well as between the lower and upper anode and the plates 14 and 85 15 respectively which tend to press the partitions and anodes tightly together under the action of screw bolts such as 16. By aid of these pressure plates and bolts the anode rings and partitions are made to form a compact self-sustaining body adapted to be removed from the rectifier vessel as a whole 90 after the cover 2 has been removed.

The anode body thus formed divides the vessel in two parts, a highly evacuated chamber 17 and an inner chamber 18 which may either be evacuated to a certain extent or may be filled with air of atmospheric pressure.

In order, now, to render the joints between the anodes, partitions and pressure plates as perfectly air-tight as possible, I arrange seals such as asbestos rings 19, 19 between them and I further cover the joints with mercury. To this end the partitions 11, 12, 13, two of which have the form of inverted perforated plates, while the lowermost one is bell-shaped, have concentric cyl-

inders 21, 22, 23 formed on the inner side, the distance between these three cylinders and between the uppermost cylinder and the anode and partition surrounding it being 5 such as to form receptacles 24, 25, 26 of annular section which may be filled with a suitable liquid, preferably a liquid metal such as mercury, such liquid forming a most perfect seal for the joints. In order to provide 10 against a connection being formed between the metal contained in the different receptacles it is preferably kept at different levels, although the concentric cylinders end at a common level. The conductors pass through 15 the metal as shown in the drawings.

In the modification shown in Fig. 2 all the partitions 27, 28, 29, 30 are bell-shaped and the three cylinders 31, 32, 33 are equal in length. In consequence thereof the same 20 tightening pressure is acting on all the anodes and the distances between the liquid surfaces are equal as well.

The modification illustrated in Fig. 3 has partitions 34 of uniform shape. Instead of 25 the cylinders forming the inner walls of the mercury seals they carry inverted funnels 35, 35 arranged on their inner sides, and similar funnels 36, 36 are disposed on the inner sides of the electrodes 37, 37, such 30 electrodes and the funnels forming part thereof being hollow, as shown at 38, in order to be fed with water or the like through hollow conductors. The interstices 39, 39 between the funnels are filled with mercury.

35 In the modification shown in Fig. 4 the partitions 40, 40 and anodes 41, 41 have different diameters and carry concentric cylinders 42, 42. The middle portion 43 of the bottom plate 44 is raised to the extent of 40 forming an inner wall for a mercury seal 45 for the joint formed between said plate and the lowermost partition.

Special advantages are derived from the arrangement shown in Fig. 5, where the hollow 45 anodes 46 as well as the partitions 47 form inverted funnels with their middle portions reinforced as at 48, 49. The bottom plate 50 offers a conical seat 51 for the lowermost partition and has an inverted 50 funnel formed on its inner face and serving as a wall for a mercury receptacle sealing the lowermost joint. The conical form of all the parts offers the advantage of self-centration and keeps the anode body as a 55 whole particularly air-tight.

All the modifications of the rectifier according to the invention illustrated in the drawings are constructed to have the arc formed on the outside of the anodes. I wish 60 it to be understood that my invention is by no means restricted to this construction, and in case that it is desired to have the arc formed on the inner side of the anodes, then the mercury seals will have to be arranged 65 on the outside.

I claim:—

1. In a composite anode body in combination, a plurality of superposed annular anodes, an annular partition intermediate two of such anodes and a liquid seal covering the joint between said anodes and said partition. 70

2. In a composite anode body in combination; a plurality of superposed annular anodes, an annular partition intermediate two of such anodes, a solid seal inserted in the joint between said anodes and said partition, and a liquid seal covering said joint. 75

3. In a composite anode body in combination, a plurality of superposed annular anodes, an annular partition intermediate two of such anodes, and a metal of low melting point covering the joint between said anodes and said partition. 80

4. In a composite anode body in combination, a plurality of superposed annular anodes, an annular partition intermediate two of such anodes, a projection of annular section on one of said parts extending upwards beyond the joint between said anodes 90 and said partition, and a liquid between said projection and said joint. 85

5. In a composite anode body in combination a conical anode ring and a conical ring of insulating material, the middle portion 95 of one of said rings being thicker than the lateral portions, a joint between said rings and a liquid seal covering said joints.

6. In a composite anode body in combination, a plurality of superposed annular anodes, an annular partition intermediate two of such anodes, a hollow projection of annular section on one of said parts extending upwards beyond the joint between said anodes and said partition, and a liquid between said projection and said joint. 100

7. In a composite anode body in combination, a plurality of superposed annular anodes, an annular partition intermediate two of such anodes, a bottom plate adjoining said partition and liquid seals covering the joints. 110

8. In a composite anode body in combination, a plurality of superposed annular anodes, an annular partition intermediate two of such anodes, plates adjoining said anodes and said partition, means for pressing said anodes, partition and plates together and liquid seals covering the joints. 115

9. In a composite anode body in combination, a plurality of superposed hollow annular anodes, and an annular partition intermediate two of such anodes, a hollow projection of annular section on said anode extending upwards beyond the joint between 120 said anodes and said partition and a liquid between said projection and said joint. 125

In testimony whereof I affix my signature.

MORITZ SCHENKEL.
